UNITED STATES PATENT OFFICE.

HAROLD S. LAMB, OF LOS ANGELES, CALIFORNIA.

VAPORIZER.

Application filed August 16, 1924. Serial No. 732,419.

This invention relates to vaporizing devices which are particularly adapted to act upon hydrocarbon compounds to provide a homogeneous thoroughly vaporized mixture for internal combustion engines.

With the carbureting equipment now in use on gasoline engines only a portion of the gasoline or other hydrocarbon is vaporized by the carburetor and the unvaporized liquid in the form of droplets is carried along with the vaporized portion to the engine. It is obvious that the molecular structure of these liquid particles of fuel is more complex than that portion which vaporizes with the atomizing effect of the carburetor, since the same force is applied to the liquid as a whole, vaporizing some and leaving the balance in a liquid state. I have found in experimenting that these unvaporized portions of the hydrocarbon cause the familiar "knocking." This, my experiments show, is brought about by the detonation of the liquid particles by pressure and excess heat.

It is the object of my invention to overcome the objections noted by removing the particles of liquid from the vaporized hydrocarbon and then converting these liquid particles into a gaseous form and then mixing the gaseous vapor with the previously vaporized products to provide a relatively cool combustible mixture of fuel wherein the molecules are of uniform size and weight.

One of the specific objects of my invention is to provide a carbureting device adapted for use with the ordinary carburetor and which is so constructed that the fluid particles remaining unvaporized after leaving the carburetor will be separated from the vaporized particles and after separation will be changed into vaporized particles and mixed with the previously formed vapors.

A further object of the invention is to provide a vaporizer including a tube or manifold having means therein for imparting a whirling action to the liquid heavy particles passing therethrough whereby the particles or droplets will be thrown off centrifugally and will be conducted to a heating device where they will be "cracked" and changed into vapor which may be conducted and mixed with the original vapor.

Another object of the invention is to provide a vaporizing device, which may be

used with any well known type of carburetor, employing a riser tube which has spiral vanes for producing a whirling action and wherein the tube is provided with an elongated slot therein for directing the whirling droplets to a heating device.

Other objects of the invention will be apparent from the following description taken in connection with the accompanying drawings wherein Fig. 1 is an elevation of a portion of an automobile engine showing my invention applied thereto; Fig. 2 is a central longitudinal, sectional view of a vaporizer embodying the features of my invention with the parts shown in elevation; Fig. 3 is an elevation of the vaporizer; Fig. 4 is a top plan view of the vaporizer and associated parts; Fig. 5 is a central, vertical, sectional view taken at right angles to the view shown in Fig. 2; Fig. 6 is a section on line 6—6, Fig. 2; Fig. 7 is a longitudinal section similar to Fig. 2 showing the action of the vaporizer; Fig. 8 is a transverse section showing the whirling effect produced; Fig. 9 is a graphic showing of a droplet of hydrocarbon and Fig. 10 is a graphic showing of a molecule of hydrocarbon.

As centrifugal forces bear a certain proportion to the weight acted upon it will be clearly seen that the action will be with increasing violence as the size and weight increase.

Liquid hydrocarbons such as gasoline and kerosene being of a heterogeneous composition having many boiling points, must be first acted upon by a spraying action which vaporizes the lighter and more volatile portions so that they are ready for combustion without being heated and should be sent directly to the cylinders. The heavier portions of the fuel require much heat to bring them to their respective boiling points and this heat must be applied to them without impairing the efficiency of the hydrocarbons that require less heat.

Referring to the drawings by reference characters, I have shown an automobile engine at 10. This engine is shown as provided with a carburetor 11, with an intake manifold 12, and with an exhaust manifold 14.

The carburetor 11 may be of any well known type. The vaporizer shown in the drawings at 15 is merely one embodiment

of my invention. It is adapted to be coupled to the carburetor by means of a coupling flange 16.

The vaporizer here shown comprises an 5 elbow portion 17, a bulbous portion 18 and a riser portion 19. The riser portion 19 is adapted to be connected with the intake manifold 12 so that a fluid tight connection is provided.

10 In the use of the well known types of carbureting equipment now on the market there is a material waste due to the fact that the carburetor merely pulverizes the fuel into small droplets which detonate when exploded in an atmosphere of great pressure and heat as in the cylinders of an engine. In the operation of the modern gasoline engine, to secure the best results, the vaporized mixture fed to the engine should be 15 homogeneous so that when the mixture is fired there will be a relatively gradual spreading of the burning action. When the droplets mentioned are present they interfere seriously with this desired even burning action, since they detonate and produce 20 the well known undesirable "knocking" effect.

I have been able to overcome the objections noted by providing a structure which 30 acts upon the mixture of vapor and droplets produced by the carburetor to give it a whirling effect. When the engine is first started this whirling effect causes the unvaporized products to fly centrifugally into 35 contact with the inner surface of the riser tube. The whirling action in the tube causes the unvaporized products after striking the inner surface of the tube to whirl about the inside of the tube until they enter 40 the slot in this riser tube whence they pass to and against a heating element so that they are heated or in other words "cracked" and are simultaneously reduced to a vaporized condition. With the present embodiment of 45 my invention, this vapor is then forced back to the intake manifold by the expansion brought about by the new droplets being vaporized. This fresh vapor upon entering the intake manifold mixes with the vapor 50 previously formed. With the use of my invention the carburetor is preferably set so that it will provide a leaner mixture than is ordinarily used since with my improvement the fuel is more completely consumed 55 by combustion.

As stated, the vaporizer 15 may be constructed with the three portions 17, 18 and 60 19 and with the portion 18 inclined toward the axis 19 as shown. Other arrangements could, however, be made without departing from the spirit of my invention.

Referring to Fig. 2 it will be noted that the elbow 17 merges into the bulbous portion 18. This bulbous portion 18 is indicated 65 as provided with spirally arranged ribs 20,

therein. Two ribs are shown and each has the same pitch and each is arranged on one half of the inner surface of the bulbous portion. These ribs or vanes increase in depth from each end toward their intermediate 70 portion so that the passageway between the ribs is of the same diameter as the diameter of the riser tube 19. It is essential that the mixture be whirled about although means other than that described may be used to 75 bring this about.

The riser tube 19 is indicated as provided with a slot 22 which leads to the rear portion of the tube. This slot 22 terminates at 80 its upper end in a circular opening 23.

The riser tube in acting as a collector for the liquid fuel must be of sufficient length to receive all of the fuel that has an outward motion imparted to it. The riser portion may be arranged in any desired manner 85 and it could be incorporated in the distributing branch of the intake manifold.

The upper end of the riser tube 19 is enlarged as at 24 and this enlarged portion is provided with an interior rabbet 25. A 90 collar 26 fits within the rabbet 25. This collar 26 has a tapering lower skirt 27 which forms a passage way between the collar 26 and the rabbeted portion 25. The riser 19 is shown as connected with the intake manifold adjacent to the collar 26 although any other arrangement could be provided if desired.

It may be here stated that my invention is adapted to be used with any type of intake and exhaust manifold so long as the intake manifold is provided with the necessary connection and the exhaust manifold is provided with the necessary heating connections to conduct heat to the vaporizing 105 element of the intake manifold.

The exhaust manifold 14 is shown in the drawings as provided with a flat portion 30 adjacent the back portion of the riser 19. The riser 19 is likewise provided with a flat 110 portion 31 and with a continuous peripheral upstanding flange 32 thereon. The flange 32 is adapted to seat against the flat portion 30 and is separated by a thin metal plate to form an elongated thin receptacle. 115 A sheet of suitable material, such as copper, is shown at 35 as arranged between the rib 32 and covering the adjacent portion 30 of the exhaust manifold. The plate 35 serves as a heat conductor as well as a 120 gasket. To insure a fluid tight joint between the plate 35 and the flange 32 a suitable member such as a thin asbestos gasket may be used. A suitable fastening member 36 serves to hold the plate 35 in place and 125 secure the vaporizer. In certain instances where excessive heat is present instead of the single plate 35, I may use a pair of plates spaced apart by means of an asbestos sheet. 130

Arranged upon the surface 31 and adjacent to the opposed sides of the slot 22 I show narrow spaced downwardly directed ribs 40. These ribs 40 terminate some distance short of the inner edge of the flange 32 and are preferably of the same thickness of this rib, whereby, in conjunction with the plate 35 they form passageways.

- The operation of my device is as follows:
- 10 The fuel enters the carburetor 11 where part of it is vaporized. This vaporized fuel with many droplets 50 (shown graphically in Fig. 9) passes to the bulbous portion 18 where the vanes 20 give it a whirling action.
  - 15 This whirling action is not sufficient to act upon the vaporized particles shown graphically in Fig. 10 but causes the droplets to be thrown against the inner surface of the riser 19. The droplets thus whirling on the
  - 20 inner surface of the riser 19 form what might be termed tiny rivulets of fuel. These rivulets are shown in Fig. 7 at 51. As the liquid rotating within the riser moves over the inner surface thereof it enters the slot 22.
  - 25 Any excess amount of fluid in the riser tube will be trapped in the space 25 and the surplus fluid will find its way through hole 23 which is an enlargement of the slot 22. The path of the whirling fuel tends to straighten out as the velocity increases but the centrifugal action increases and the liquid fuel is thrown out with greater violence. This improves the volumetric efficiency at higher speeds.
  - 35 After the fluid passes through the slot 22 it moves down the passageways 54 which are provided by means of the inclined ribs 40. The spaces 54 and in fact the entire receptacle adjacent the plate 35 are extremely narrow. The liquid fuel adjacent the plate 35 is now heated and is changed to vapor. In other words, droplets 50 as shown in Fig. 9 are reduced to the molecules as shown in Fig. 10 at 55.

- 45 When the droplets are thus vaporized, their volume is increased and the pressure is increased so that this freshly formed vapor is pressed back into the intake manifold where it moves with the vapor already produced and provides a homogeneous mixture for the engine cylinders.

- The above operation takes place when the engine is started from a "cold" condition. After the engine has been running some time the heat from the exhaust manifold 14 heats the riser tube 19 so that some of the droplets are vaporized when whirled and thrown against the inner surface of the tube. Any droplets not thoroughly vaporized will find their way through the slot 22 and will be vaporized in the heating receptacle.

Having thus described my invention, I claim:

- 65 1. A vaporizer comprising a conduit for a

vaporous fuel mixture, means arranged along the inner surface of the conduit for trapping fuel particles in the vapor, a device in communication with the conduit for vaporizing the fuel particles comprising a 70 chamber associated with the conduit, a plate covering the chamber against which the fuel particles are vaporized, means for heating the plate and means for permitting the vapor so formed to mingle with the vaporous 75 fuel mixture previously formed.

2. In a vaporizer including an elongated tube having a bulbous portion therein, spiral vanes arranged on the inner wall of said bulbous portion to provide an unobstructed 80 passage, said tube having an opening in the wall thereof separate from and beyond said vanes, a collar within said tube, said collar being spaced from the tube to form an annular fuel trapping cavity, an element 85 adapted to be heated adjacent to said tube, means for heating said element said opening enabling particles separated from the vapor to be distributed over said heated element.

3. A vaporizer including a tube having a bulbous portion therein, spiral vanes arranged in said bulbous portion, said tube having an aperture in one portion of the wall thereof, said aperture being separate 90 from and beyond said vanes, a receptacle arranged at one side of said tube, a plate adapted to fit over said receptacle, means whereby said plate may be heated from an exhaust manifold, said portion of the wall 100 of the tube having the aperture therein having said receptacle thereon, said aperture affording communication to the receptacle, thus allowing the fluid particles separated from the vapor to pass through said aperture and impinge upon said plate.

4. In a vaporizer including a tube having an enlargement therein, means associated with the enlargement for rotating fluid particles passing therethrough, said tube having an aperture in the wall thereof, said aperture being separate from and beyond said means, said tube having a flanged portion thereon, a plate adapted to fit said flanged portion to form a receptacle, means to heat said plate, said aperture being arranged in the portion of the wall of the tube which is adjacent to said plate thus enabling particles separated from the vapor to pass 115 through the aperture and to impinge upon said plate.

5. In a vaporizer including a tube having a bulbous portion therein, spiral vanes arranged in said bulbous portion, the inner diameter of said spiral vanes being of the same diameter as the internal diameter of the tube, a rabbeted portion adjacent one end of said tube, a collar adapted to fit within said tube adjacent said rabbet, said collar being spaced from said tube to provide a 125

groove, an element adapted to be heated, means for heating said element, said vanes being adapted to separate fluid particles from the vapor and means to permit the 5 passage of the fluid particles separated from the vapor to said element.

6. In a vaporizer, including a tube having a bulbous portion therein, spiral vanes arranged in said bulbous portion, the inner diameter of said spiral vanes being of the 10 same diameter as the internal diameter of the tube whereby an unobstructed passage is formed, a slot in said tube having an en-

larged upper end, a continuous flange on said tube extending thereabout, a plate 15 adapted to fit said flange to form a receptacle, means for heating the plate, said slot enabling fluid particles separated from the vapor to be distributed over said plate, the upper end of said tube being enlarged to 20 form a cavity for trapping the excess of droplets so that they may pass through the enlarged end of said slot.

In testimony whereof, I hereunto affix my signature.

HAROLD S. LAMB.
